SEWING MACHINE WITH AUTOMATIC
DISAPPEARING TREADLE

Ludwig J. Fichter and Ralph R. Pierson, Rockford, Ill., assignors to Free Sewing Machine Co., Rockford, Ill., a corporation of Illinois

Application April 2, 1948, Serial No. 18,667

18 Claims. (Cl. 312—26)

1

This invention relates to treadle operated sewing machines, and is particularly concerned with the provision of means for automatically causing the folding and unfolding of the treadle to and from a concealed position in the lowering and raising of the head to and from a folded inoperative position.

The salient feature of our invention is the provision of a longitudinally extending shaft mounted in bearings under the working top of the sewing machine cabinet and operatively connected with the hinged cover panels, to be oscillated automatically in the folding and unfolding of said panels, the shaft having one arm fixed thereon providing a fold-down type support for the head, and having another arm fixed thereon which is operatively connected through a linkage and bell-crank mechanism with a hinged treadle supporting panel mounted in the cabinet on one side of the leg-space to swing down laterally into operative position. With this combination, the drop head in gravitating from its raised operative position to its lowered inoperative position supplies more force than required to raise the treadle carrying panel. Included in the linkage and bell-crank mechanism referred to is a closely coiled tension spring interconnecting the lower end of the main link with the bell-crank to provide a positive connection for push operation, as in unfolding the treadle supporting panel, and a yieldable connection in the opposite direction, namely, when folding the panel upwardly into the side of the cabinet, whereby to compensate for minor irregularities in quantity production of the machines and at the same time avoid danger of serious injury to the operator or a child standing nearby when the panel is folded up, in the event fingers should be caught between the parts. The spring connection, incidentally, provides a convenient means of threadedly adjusting the link connection to lengthen or shorten the effective length of the main link connection, as required in the original assembling of the machine at the factory.

The invention is illustrated in the accompanying drawings, in which—

Fig. 1 is a front phantom view of a sewing machine cabinet showing the foldable head actuating and foldable treadle actuating mechanism in full lines, the treadle being illustrated in its unfolded operative position;

Fig. 2 is a view similar to Fig. 1, showing the treadle folded up and the head folded down;

Figs. 3 and 4 are end views of Figs. 1 and 2, respectively;

2

Fig. 5 is a detail on the line 5—5 of Fig. 1, and Fig. 6 is an enlarged detail, partly in section and partly in elevation, of the adjustable spring connection between the main operating link and the bell-crank.

The same reference numerals are applied to corresponding parts throughout the views.

Referring to the drawings, the cabinet illustrated in phantom comprises a top 7, over which two cover panels 8 and 8a are foldable inwardly from opposite ends, the same being hinged at the ends of the top 7, as indicated at 9 and 9a. The top 7 is supported on legs 10 and 11 leaving leg-space 12 therebetween. The leg portion 10 is of hollow construction without drawers, the other leg portion 11 including drawers 13, which may extend the full depth of the cabinet to store the sewing materials. In the inner side wall 14 of the leg portion 10, an opening 15 is provided, 10 in which a treadle supporting panel 16 has a free working fit, the same being hinged to the cabinet at its lower end, as indicated at 17, to swing laterally and downwardly from the folded vertical position of Fig. 2 to the unfolded horizontal operative position shown in Fig. 1. Metal or rubber bumpers 18 are provided on the outer end of the panel 16 to rest on the floor, and thus keep the panel out of contact with the floor so long as the treadle 19 is in use. The head 20 is hinged by means of the usual bed plate 21 to the top 7, in the usual way, as indicated at 22, to drop down in the opening 23 when the machine is folded, and there is a specially designed front bib section 24 hinged at 25 to the bed plate 21, to fill out the front portion of the opening 23 in front of the bed plate 21 when the head is raised. This bib section has at its opposite ends downwardly curved laterally and forwardly projecting lugs 24a on the bottom thereof at the forward edge, which ride under the top 7 at the opposite ends 15 of the bed plate opening at the end of the upward movement of the head, to assure unfolding to coplanar relationship of the bib 24 with the top 7 and bed plate 21, and at the same time 20 cause the forward edge portion of the bib 24 to ride into place on top of supporting blocks 24b, provided in the cabinet on the back of the front cross-piece 24c under the top at the front corners of the bed plate opening, whereby the 25 bib portion 24 assumes a fair degree of support of the head in the final raised position, instead of the arm 51 having to assume the entire load. This construction also makes for a better working top by eliminating the sense of yielding 30 under downward pressure on the forward portion of the bed plate. There is sufficient friction

at the pivotal connections 25 to assure maintaining the bib 24 at the angularity illustrated in Fig. 4 relative to the bed plate 21 after it has been moved to that angle as it rides off the blocks 24b in the dropping of the head 20, so that there will be nothing to interfere with the bib 24 being unfolded again later by the sliding of the lugs 24a against the under side of the top 7 the next time the head is raised. If desired, suitable friction washers may be provided at the pivotal connections 25 to give the desired friction. Fig. 1 shows the machine ready for use with the head 20 raised to operative position and the treadle 19 lowered to operative position, the treadle being arranged to operate the fly wheel 26 by means of a pitman rod 27 attached to the crank 28 on the flywheel, and the fly wheel being arranged to transmit drive to the pulley 29 on the end of the head 20 by means of the usual belt 30, the usual hand wheel being shown next to the pulley 29 on the head 20 at 31. When the machine is folded, as illustrated in Fig. 2, the head 20 is dropped down and is concealed under the covers 8 and 8a, and the panel 16 is folded upwardly concealing the treadle 19, which folds up with it into the leg 10.

The treadle 19 is slidably and oscillatably mounted by means of bearings 32 on a shaft 33 supported at its ends in brackets 34 fastened to the inner side of panel 16. A laterally and forwardly reaching arm 35, which in the old style treadle machine was pivotally connected directly to the lower end of the pitman rod operating the flywheel, is here only provided with a forwardly reaching stub axle 36, at right angles to and pivotally engaging in a transverse hole provided in the adjacent end of the spindle 37. This spindle is rotatably mounted at its other end in bearing 38 on rod 27 on a fixed axis at right angles to said rod, so that oscillation of the treadle 19 transmits reciprocatory movement to rod 27 to turn the fly wheel 26, and the treadle may, nevertheless, be moved through ninety degrees (90°) relative to spindle 37, as shown in Fig. 2. It will be noticed that rod 27, which is normally in a plane substantially parallel to the fly wheel 26, is swung laterally to the extent shown in Fig. 2 when the treadle is folded up into the cabinet. The bearing 39 on the upper end of the rod 27 is constructed to permit this small angle of oscillation of the rod 27 relative to the crank pin 28, or the rod 27 may itself have sufficient flexibility to give to this extent. Now, a horizontal shaft 40 extends lengthwise of the cabinet under top 7 and is supported for oscillation in bearings 41 secured to the under side of said top, and this shaft is arranged to be oscillated, as will soon appear, in response to pivotal movement of cover panel 8. An arm 42 fixed to one end of this shaft has one end of a link 43 pivotally connected thereto and extending downwardly inside the cabinet leg 10 and pivotally connected at its other end by means of a closely coiled tension spring 44 to one arm of a bell-crank lever 45. The latter is pivotally mounted, as at 46, on a block fastened to the back wall of the cabinet in the lower portion of the cabinet leg 10, and has its other arm pivotally connected to one end of a short link 47, which, in turn, is pivotally connected at its other end to the treadle 19 supporting panel 16, as at 48, in radially outwardly spaced relation to the axis of pivots 17 for said panel. In that way, the arm 42 in approximately ninety degree (90°) movement from the position shown in Figs. 1 and 3 to that shown

in Figs. 2 and 4 is adapted to cause the folding up of panel 16 with the treadle 19 from the exposed operative position to the concealed inoperative position, and vice versa. The spring 44, in the unfolding operation, acts as a positive link element, like link 43, transmitting downward push to the associated arm of bell-crank 45. On the other hand, in the folding operation, spring 44 exerts a yielding pull on the bell-crank arm, which is of advantage in several ways: It compensates for such slight variations in the cabinets and in the link and lever mechanism as are bound to occur in quantity production and hurried assembly of sewing machines, and, what is more important, it affords a safety feature in providing the give needed in the event the operator or a child standing nearby should happen to get fingers caught between the cabinet and the panel 16 in the closing of the latter. By providing a helical groove 49 in the lower end of the link 43, as shown in Fig. 6, and threading the upper end of spring 44 in this groove, we also are enabled easily to change the effective length of the main operating link connection 43-44, as may be necessary in the assembly of the machines at the factory, the spring 44 being merely disconnected from the lever 45 at 50 and screwed up or down on link 43 one or more turns, as conditions require, and reconnected at 50. This means quite a saving in assembling time.

The force required to raise the panel 16 and treadle 19 is supplied by the gravitation of the head 20 from its raised operative position (Figs. 1 and 3) to its lowered inoperative position (Figs. 2 and 4), there being an arm 51 fixed to the shaft 40 intermediate the ends thereof under the bed plate 21 and serving as a support for the drop head, as best illustrated in Fig. 3, where the head is shown in its raised operative position. By locating the arm 51 substantially in the vertical plane through the center of gravity of the head and bed plate, it is obvious that we are assured of easiest operation, and we also provide a roller 52 mounted in a depending leg 53 on the bottom of the bed plate 21 at the free forward edge thereof, which has rolling contact on the flat top track surface 54 provided on the arm 51 and makes for quiet and easy operation when the parts move from the position shown in Fig. 3 to that shown in Fig. 4. Now, the cover panel 8 has a short link 55 pivotally connected at one end to the panel 8 in radially outwardly spaced relation to the hinging axis of said panel, as shown in Fig. 1, and this link rides on a roller 57 mounted in a bracket 58 fastened to the end wall of the cabinet. A chain 59 is pivotally connected to the free end of the link 55, as clearly appears in Fig. 1, and is adjustably connected at its other end by means of a screw 60 to a radial arm 61 provided on one end of a segmental-shaped roller 62 that is suitably fixed to the end of the shaft 40. A nut 63 threading on the screw 60 can be adjusted to provide exactly the correct length of flexible connection between the panel 8 and the arm 61 to turn the shaft 40 through approximately ninety degrees (90°) in one hundred eighty degree (180°) movement of the cover panel 8, from the folded position of Fig. 2 to the unfolded position of Fig. 1, whereby to raise the head 20 to operative position and at the same time unfold the treadle 19 to operative position. A lock nut 64 threading on the screw 60 can be tightened against the adjusting nut 63 to maintain the adjustment.

A transversely curved dust and oil drip guard

65 is provided extending between the legs 10 and 11, and the arm 51 operates within the radius of this curved guard.

It is believed the foregoing description conveys a good understanding of the objects and advantages of my invention. The appended claims have been drawn to cover all legitimate modifications and adaptations.

We claim:

1. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, a longitudinally extending shaft supported in a substantially horizontal position in bearings under the working top, means providing an operating connection between the hinged cover panel and the adjacent end of said shaft, whereby the shaft is oscillated through a predetermined angularity in response to one hundred eighty degree (180°) unfolding movement of the cover panel, means intermediate the ends of said shaft operatively connecting the head with the shaft, whereby the head is raised to and supported in operative position in the aforesaid oscillatory movement of the shaft, a flywheel mounted in one end of said cabinet below the aforesaid hand wheel and pulley and adapted to be drivingly connected by a belt with the pulley, a treadle oscillatably mounted on a support that is pivoted on a substantially horizontal axis relative to the lower portion of the flywheel containing end of said cabinet so as to be foldable from a substantially horizontal operative position upwardly to an inoperative position, a pitman rod connected at its upper end to a crank-pin on the flywheel and having a universal joint connection at its lower end with a laterally reaching arm provided on said treadle, and means operatively connecting the treadle support with the adjacent end of said shaft remote from the hinged cover panel, whereby the treadle support is unfolded from its vertical inoperative position to its horizontal operative position in the aforesaid oscillatory movement of the shaft.

2. In a sewing machine of the drop head type, a cabinet providing a working top, a head pivoted thereon to swing downwardly to a position below the plane of the working top of said cabinet, a cover panel for the working top hinged to one end of the cabinet, a longitudinally extending shaft supported in a substantially horizontal position in bearings under the working top, means providing an operating connection between the hinged cover panel and the adjacent end of said shaft, whereby the shaft is oscillated through a predetermined angularity in response to one hundred eighty degree (180°) unfolding movement of the cover panel, means intermediate the ends of said shaft operatively connecting the head with the shaft, whereby the head is raised to and supported in operative position in the aforesaid oscillatory movement of the shaft, a flywheel mounted in said cabinet drivingly connected by a belt with the head, a treadle oscillatably mounted on a support that is pivoted on a substantially horizontal axis relative to the lower portion of said cabinet so as to be foldable from a substantially horizontal operative position upwardly to an inoperative position, a pitman rod connected at its upper end to a crank-pin on the flywheel and having a universal joint connection at its lower end with a laterally reaching arm provided on said treadle, and means operatively connecting the treadle support with the shaft, whereby the treadle support is unfolded from its vertical inoperative position to its horizontal operative position in the aforesaid oscillatory movement of the shaft, the last mentioned means including a push and pull link and lever mechanism adapted to push the treadle support from folded inoperative position to unfolded operative position and pull it in the opposite direction, and said mechanism including a closely coiled tension spring, which in the push operation operates as a positive link element, but which in the pull operation operates as a yieldable tension element, substantially as and for the purpose described, said tension spring being furthermore threadedly connected with one of the links of the link and lever mechanism for length adjustment of one of the link connections.

4. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, a longitudinally extending shaft supported in a substantially horizontal position in bearings under the working top, means providing an operating connection between the hinged cover panel and the adjacent end of said

lower end with a laterally reaching arm provided on said treadle, and means operatively connecting the treadle support with the shaft, whereby the treadle support is unfolded from its vertical inoperative position to its horizontal operative position in the aforesaid oscillatory movement of the shaft, the last mentioned means including a push and pull link and lever mechanism adapted to push the treadle support from folded inoperative position to unfolded operative position and pull it in the opposite direction, and said mechanism including a closely coiled tension spring, which, in the push operation, operates as a positive link element, but which in the pull operation operates as a yieldable tension element, substantially as and for the purpose described.

3. In a sewing machine of the drop head type, a cabinet providing a working top, a head pivoted thereon to swing downwardly to a position below the plane of the working top of said cabinet, a cover panel for the working top hinged to one end of the cabinet, a longitudinally extending shaft supported in a substantially horizontal position in bearings under the working top, means providing an operating connection between the hinged cover panel and the adjacent end of said shaft, whereby the shaft is oscillated through a predetermined angularity in response to one hundred eighty degree (180°) unfolding movement of the cover panel, means intermediate the ends of said shaft operatively connecting the head with the shaft, whereby the head is raised to and supported in operative position in the aforesaid oscillatory movement of the shaft, a flywheel mounted in said cabinet drivingly connected by a belt with the head, a treadle oscillatably mounted on a support that is pivoted on a substantially horizontal axis relative to the lower portion of said cabinet so as to be foldable from a substantially horizontal operative position upwardly to an inoperative position, a pitman rod connected at its upper end to a crank-pin on the flywheel and having a universal joint connection at its lower end with a laterally reaching arm provided on said treadle, and means operatively connecting the treadle support with the shaft, whereby the treadle support is unfolded from its vertical inoperative position to its horizontal operative position in the aforesaid oscillatory movement of the shaft, the last mentioned means including a push and pull link and lever mechanism adapted to push the treadle support from folded inoperative position to unfolded operative position and pull it in the opposite direction, and said mechanism including a closely coiled tension spring, which in the push operation operates as a positive link element, but which in the pull operation operates as a yieldable tension element, substantially as and for the purpose described, said tension spring being furthermore threadedly connected with one of the links of the link and lever mechanism for length adjustment of one of the link connections.

5. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, a longitudinally extending shaft supported in a substantially horizontal position in bearings under the working top, means providing an operating connection between the hinged cover panel and the adjacent end of said

shaft, whereby the shaft is oscillated through a predetermined angularity in response to one hundred eighty degree (180°) unfolding movement of the cover panel, a head supporting and oscillating arm fixed to said shaft under the head and movable upwardly in the aforesaid oscillation of said shaft to raise the head to operative position, another arm in transverse relation to the first arm fixed to and oscillating with the other end of said shaft remote from the hinged panel, a flywheel mounted in one end of said cabinet below the aforesaid hand wheel and pulley and adapted to be drivingly connected by a belt with the pulley, a treadle oscillatably mounted on a support that is pivoted on a substantially horizontal axis relative to the flywheel containing end of said cabinet so as to be foldable upwardly from a substantially horizontal operative position to an inoperative position, a pitman rod connected at its upper end to a crank-pin on the flywheel and having a universal joint connection at its lower end with a laterally reaching arm provided on said treadle, and means operatively connecting the last mentioned arm with the treadle support, whereby to unfold the treadle support to operative position in the aforesaid oscillatory movement of the shaft.

5. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, means operatively connecting said head with said cover panel to raise the head to and support the same in operative position in one hundred eighty degree (180°) unfolding movement of the cover panel, a flywheel mounted in one end of said cabinet below the aforesaid hand wheel and pulley and adapted to be drivingly connected by a belt with the pulley, a treadle oscillatable relative to the flywheel containing end of said cabinet and foldable from a substantially horizontal operative position upwardly to an inoperative position, a pitman rod connected at its upper end to a crank-pin on the flywheel and having a universal joint connection at its lower end with a laterally reaching arm provided on said treadle, and means operatively connecting the cover panel with said treadle to unfold the treadle to operative position in the same one hundred eighty degree (180°) unfolding movement of the cover panel.

6. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, means operatively connecting said head with said cover panel to raise the head to and support the same in operative position in one hundred eighty degree (180°) unfolding movement of the cover panel, a flywheel mounted in one end of said cabinet below the aforesaid hand wheel and pulley and adapted to be drivingly connected by a belt with the pulley, a treadle oscillatable relative to the flywheel containing end of said cabinet and foldable from a substantially horizontal operative position upwardly to an inoperative position, a pitman rod connected at its upper end to a crank-pin on the flywheel and having a universal joint connection

5 at its lower end with a laterally reaching arm provided on said treadle, and means connected with the head raising and supporting means for folding and unfolding the treadle in the lowering and raising of the head, so that the weight of the head in gravitating to its lowered position supplies the force needed to raise the treadle to its folded inoperative position.

7. In a sewing machine of the drop head type, a cabinet providing a working top, a head pivoted thereon to swing downwardly to a position below the plane of the working top of said cabinet, said head including a hand wheel and pulley on one end, a cover panel for the working top hinged to one end of the cabinet remote from the hand wheel and pulley, a flywheel mounted in one end of said cabinet below the aforesaid hand wheel and pulley and adapted to be drivingly connected by a belt with the pulley, a treadle foldable with respect to the flywheel end of said cabinet to and from a substantially horizontal operative position, a pitman rod connected at its upper end to a crank-pin on the flywheel and having a universal joint connection at its lower end with a laterally reaching arm provided on said treadle, and means operatively connecting the cover panel with the treadle so as to unfold the treadle to operative position in one hundred eighty degree (180°) unfolding movement of the cover panel.

8. In a sewing machine of the drop head type, the combination of a cabinet providing a working top having an opening provided therein for a bed plate, a head including a bed plate pivoted to said cabinet in said opening to swing downwardly to a position below the plane of said working top, a cover panel for said cabinet hinged with respect to one end of said working top and operatively connected with the head to swing the same upwardly to and support the same in operative position in one hundred eighty degree (180°) unfolding movement of the cover panel, a front panel pivoted to the front portion of the bed plate unfoldable to coplanar contiguous relation with the bed plate when the head is raised to operative position, means on the cabinet providing a supporting ledge for the front edge portion of said front panel to support the same in coplanar relation with the working top, and guide projections on the bottom of said front panel at its forward edge at opposite ends arranged to slide on the bottom of the working top of said cabinet at opposite ends of the aforesaid opening to cause the unfolding of the front panel to coplanar relationship with the bed plate and guide it into position over the aforesaid supporting ledge.

9. In a sewing machine of the drop head type, the combination of a cabinet providing a working top having an opening provided therein for a bed plate, a head including a bed plate pivoted to said cabinet in said opening to swing downwardly to a position below the plane of said working top, a cover panel for said cabinet hinged with respect to one end of said working top and operatively connected with the head to swing the same upwardly to and support the same in operative position in one hundred eighty degree (180°) unfolding movement of the cover panel, a front panel pivoted to the front portion of the bed plate unfoldable to coplanar contiguous relation with the bed plate when the head is raised to operative position, means on the cabinet providing a supporting ledge for the front edge portion of said front panel to support the same in coplanar relation with the working top, and guide projections on the bottom of said front panel at its

forward edge at opposite ends arranged to slide on the bottom of the working top of said cabinet at opposite ends of the aforesaid opening to cause the unfolding of the front panel to coplanar relationship with the bed plate and guide it into position over the aforesaid supporting ledge, the pivotal mounting for said front panel frictionally resisting pivotal movement thereof relative to the bed plate sufficiently to maintain the front panel at a predetermined angularity relative to the bed plate in its lowered position, to which angularity the panel moves in sliding off the ledge in the lowering of the head.

10. In a sewing machine of the drop head type, a cabinet providing a working top, a head pivoted thereon to swing downwardly to a position below the plane of the working top of said cabinet, a cover panel for the working top hinged to one end of the cabinet, a flywheel mounted in said cabinet drivingly connected by a belt with the head, a treadle foldable with respect to the cabinet to and from a substantially horizontal operative position, a pitman rod connected at its upper end to a crank-pin on the flywheel and having a universal joint connection at its lower end with a laterally reaching arm provided on said treadle, and link and lever mechanism operatively connecting said foldable treadle with the cover panel to fold and unfold the treadle in the folding and unfolding of the cover, said link and lever mechanism including a closely coiled tension spring, which in the unfolding of the treadle acts as a positive push link element, but which in the folding of the treadle acts as a yieldable tension spring element, substantially as and for the purpose described.

11. A sewing machine as set forth in claim 10, wherein one of the link elements of said link and lever mechanism is adjustably threadedly connected with one end of said tension spring for a length adjustment of the link.

12. In a sewing machine, a cabinet providing a working top and depending leg portions, one of which is hollow, a flywheel mounted in the hollow leg of said cabinet, a head supported on said cabinet with which said flywheel is adapted to be operatively connected by a belt, the hollow leg portion of said cabinet having an opening provided in the inner side wall thereof, a panel pivotally mounted at its one end on a horizontal axis in the lower portion of said opening to swing upwardly and form a closure for said opening, a treadle oscillatably mounted directly on the inner side of said panel so as to swing with it to and from its vertical closed position, and a pitman rod connected at its upper end to a crank-pin on the flywheel and having a universal joint connection at its lower end with a laterally reaching arm provided on said treadle.

13. In a sewing machine, a cabinet providing a working top and depending leg portions, one of which is hollow, a flywheel mounted in the hollow leg of said cabinet, a head supported on said cabinet with which said flywheel is adapted to be operatively connected by a belt, the hollow leg portion of said cabinet having an opening provided in the inner side wall thereof, a panel pivotally mounted in the lower portion of said opening to swing upwardly and form a closure for said opening, a treadle oscillatably mounted on the inner side of said panel, a pitman rod connected at its upper end to a crank-pin on the flywheel and having a universal joint connection at its lower end with a laterally reaching arm provided on said treadle, a bell-crank pivoted in

5 the lower portion of said hollow leg and having one arm thereof operatively connected by a link with the pivoted end portion of said panel, a link pivotally connected with the other arm of said bell-crank extending upwardly in the hollow leg, and a cover panel hinged to the working top of said cabinet and operatively connected with the upper end of the last mentioned link so as to push downwardly thereon in the unfolding of the cover panel and pull upwardly thereon in the folding of said cover panel.

14. A structure as set forth in claim 13, including a closely coiled tension spring forming the connecting element between the upwardly extending last mentioned link and the associated arm of said bell-crank, and adapted to serve as a positive push element in the unfolding of the treadle supporting panel and as a yieldable tension spring in the folding of said panel, substantially as and for the purpose described.

15. In a sewing machine, a cabinet providing a working top and depending leg portions, a cover hinged to the working top to unfold into substantially coplanar relationship thereto, one of the depending leg portions of the cabinet forming an enclosure, a panel forming an inner side wall of said enclosure and pivotally mounted at its lower end to swing downwardly to a substantially horizontal position in which it is adapted to serve as a treadle support, a bell-crank pivoted in the lower portion of said enclosure and having one arm thereof operatively connected by a link with the pivoted end portion of said panel, another link pivotally connected with the other arm of said bell-crank and extending upwardly in said enclosure and operatively connected at its upper end with the cover, so that the cover pushes downwardly on said last mentioned link in the unfolding of the cover to unfold the panel and pulls upwardly on said link in the folding of said cover to swing said panel upwardly to closed position.

16. A structure as set forth in claim 15, including a closely coiled tension spring forming the connecting element between the upwardly extending last mentioned link and the associated arm of said bell-crank, and adapted to serve as a positive push element in the unfolding of the treadle supporting panel and as a yieldable tension spring in the folding of said panel, substantially as and for the purpose described.

17. In a sewing machine, a cabinet providing a working top and depending leg portions, a cover hinged to the working top to unfold into substantially coplanar relationship thereto, one of the depending leg portions of the cabinet forming an enclosure, a panel forming an inner side wall of said enclosure and pivotally mounted at its lower end to swing downwardly to a substantially horizontal position in which it is adapted to serve as a treadle support, a bell-crank pivoted in the lower portion of said enclosure and having one arm thereof operatively connected by a link with the pivoted end portion of said panel, another link pivotally connected with the other arm of said bell-crank and extending upwardly in said enclosure and operatively connected at its upper end with the cover, so that the cover pushes downwardly on said last mentioned link in the unfolding of the cover to unfold the panel and pulls upwardly on said link in the folding of said cover to swing said panel upwardly to closed position, a flywheel mounted in said enclosure and adapted to be operatively connected by means of a belt with a head support on the working top, a treadle oscillatably mounted on the inner side

of said panel and slidable endwise along its axis of oscillation relative to said panel, and a pitman rod connected at its upper end to a crank-pin on the flywheel and having a universal joint connection at its lower end with a laterally reaching arm provided on said treadle. 5

18. In a sewing machine, a cabinet providing a working top and depending leg portions, one of which provides an enclosure, a panel forming an inner side wall of said enclosure and pivoted at its lower end on a substantially horizontal axis to swing downwardly to a substantially horizontal position in which it is adapted to serve as a treadle support, a flywheel mounted in said enclosure and adapted to be operatively connected by a belt with a head supported on the working top, a treadle oscillatably mounted on the inner side of said panel and slidable endwise along its axis of oscillation relative to said panel, 10 15

and a pitman rod connected at its upper end to a crank-pin on the flywheel and having a universal joint connection at its lower end with a laterally reaching arm provided on said treadle.

LUDWIG J. FICHTER.
